UNITED STATES PATENT OFFICE.

ARCHIBALD E. PRESTON, OF FILLMORE, CALIFORNIA.

PUMP-PLUNGER.

1,195,395.

Specification of Letters Patent. Patented Aug. 22, 1916.

Application filed April 28, 1915. Serial No. 24,458.

To all whom it may concern:

Be it known that I, ARCHIBALD E. PRESTON, a citizen of the United States, residing at Fillmore, in the county of Ventura 5 and State of California, have invented new and useful Improvements in Pump-Plungers, of which the following is a specification.

This invention relates to a pump plunger 10 which is particularly designed for use in oil wells.

The pumps now commonly used in the oil fields are constructed of a barrel and plunger and two valves, one of which is attached to the top of the plunger and the other at the bottom of the barrel. The plunger proper generally consists of a single cylinder which is ground at considerable labor and expense to fit the barrel within 20 one thousandth of an inch. Upon being placed in the well, the plunger rapidly wears and in a greater or less time does not fit the barrel, allowing the fluid or oil to slip past until finally the pump no longer operates. Furthermore, the wear allows sand 25 to settle around the plunger and prevents it from operating, this being known as sanding up a pump.

The object of the present invention is to 30 provide a plunger which eliminates the necessity of grinding and fitting with relation to the barrel, and, furthermore, to provide a plunger which automatically takes up the wear by the expansion of the component 35 parts, obviating the troubles heretofore mentioned.

Further objects will hereinafter appear.

The invention consists of the parts and the construction and combination of parts 40 as hereinafter more fully described and claimed, having reference to the accompanying drawings, in which—

Figure 1 is a side elevation of the plunger. Fig. 2 is a vertical, central section 45 through same. Fig. 3 is a cross section on line 3—3 of Fig. 1. Fig. 4 is a side elevation, showing a modification of the construction employed in Fig. 1. Fig. 5 is a vertical, central section through Fig. 4. Fig. 6 is 50 a cross section on line 6—6 of Fig. 4.

More particularly described, the preferred form of plunger shown in Figs. 1, 2 and 3 consists of an inner cylinder 2, exteriorly of which is mounted a split sleeve 3, the length 55 of which is practically the same as the inner cylinder 2. Mounted exteriorly of the split

sleeve 3 are two similar sleeves 4 and 5, and securing said expansion sleeves with relation to cylinder 2 is an upper and a lower nut 6 and 7 respectively. 8 indicates gaskets 60 of suitable material interposed between the expansion sleeves and the nuts. These gaskets are provided for the purpose of preventing the admission of sand between the inner cylinder and the expansion sleeves and 65 are mounted sufficiently loose to permit the sleeves to gradually expand as wear takes place. The upper nut 6 may be provided with an exterior thread 9 to receive the upper cage or valve (not here shown). 70

Referring to Figs. 1 and 2, it will be seen that the splits in the exterior sleeves 4 and 5 are offset with relation to each other or set out of alinement for the purpose of preventing leakage therethrough. The sleeves are 75 secured or retained in this position by means of pins or rivets 10 secured in the inner sleeve 3 and projecting into slots 11 formed on the respective exterior sleeves. The sleeves are thus free to expand as wear 80 takes place but are at the same time prevented from turning with relation to each other, thus obviating any possibility of the sleeves or openings in the sleeves from coming into alinement. By this construction 85 grinding or close fitting of the plunger with relation to the barrel is obviated and at the same time wear is automatically taken up, as the sleeves will gradually and automatically expand as wear takes place. 90

In Figs. 4, 5 and 6 a modification has been shown. In this instance the inner cylinder 2 is provided with a shoulder 12 and a threaded extension 13 which serves the same function as the nut 6 shown in Figs. 1 and 2. 95 The inner expansion sleeve 3 is also entirely eliminated and in its place two split sleeves 4^a and 5^a have been provided. The faces of these sleeves are provided with a plurality of annular grooves 14 in each of which 100 is mounted a common expansible piston ring 15, such as is commonly used in connection with internal combustion engines; the main expansion sleeves 4^a and 5^a being secured in position by means of a lower nut 16. This 105 particular type of plunger is very efficient where little or no sand is encountered, while the plunger shown in Figs. 1, 2 and 3 is particularly constructed where sand in greater or less quantities is contained in the 110 oil.

A plunger constructed as here shown can

be cheaply manufactured as exact fitting and grinding with relation to the barrel is entirely eliminated. The automatic expansion of the several sleeves provided prevents 5 leakage past the plunger and at the same time takes up all the wear both in the barrel and on the plunger, thus obviating all the troubles heretofore mentioned including sanding up of the pump. The plunger can 10 be made in any length from a few inches to several feet and may be used for other purposes besides oil well pumps.

The materials and finish of the several 15 parts of the apparatus are such as the experience and judgment of the manufacturer may dictate.

I wish it understood that various changes 20 in form, proportions and minor details of construction may be resorted to within the scope of the appended claim and that I do not wish to limit myself to the specific design and construction here shown.

Having thus described my invention, what I claim and desire to secure by Letters Patent is—

A pump plunger comprising a cylinder, an expansible sleeve surrounding the cylinder, means for holding the sleeve on the cylinder, a pair of outwardly extending pins fixed on the sleeve in offset relation, and a 30 pair of split expansible sleeves encircling the first sleeve, each sleeve of said pair having opposing recesses in the walls of its split to form a circumferential slot for freely receiving one of said pins whereby limited 35 sliding movement between the inner and outer sleeves is obtained.

In testimony whereof I have hereunto set my hand in the presence of two subscribing witnesses.

ARCHIBALD E. PRESTON.
